W. MOORE.
Steam Boiler and Furnace.

No. 227,813.

Patented May 18, 1880.

UNITED STATES PATENT OFFICE.

WILLIAM MOORE, OF KOKOMO, INDIANA.

STEAM-BOILER AND FURNACE.

SPECIFICATION forming part of Letters Patent No. 227,813, dated May 18, 1880.

Application filed February 5, 1880.

To all whom it may concern:

Be it known that I, WILLIAM MOORE, of Kokomo, Howard county, Indiana, have invented a new and useful Improvement in Steam-Boilers and Furnaces, of which the following is a specification.

My invention relates to improvements in steam-boilers and their furnaces, designed to produce a more perfect combustion of the fuel employed, with especial regard to portable boilers used for driving farm machinery, and in which light fuels, such as hay, straw, grasses, corn-stalks, brush, &c., are used for generating steam.

It consists in a certain combination and organization of parts, as will be hereinafter more fully set forth.

My invention is embodied in the mechanism illustrated in the drawings accompanying this specification, in which—

Figure 1 is a front-end elevation of my improved boiler. Fig. 2 is a rear-end elevation of the same. Fig. 3 is a central vertical longitudinal section of the same. Fig. 4 is a vertical cross-section of same, taken through the furnace; and Fig. 5 is a vertical cross-section taken through the rear smoke-arch.

In the illustration of my invention I have shown a boiler, A, of the improved Cornish type, having a main or fire-box flue, B, and return-flues C. The main flue B is arranged eccentrically with the shell of the boiler, with which it is united at the bottom, this form of boiler possessing the advantage of admitting a large main flue, and therefore being best adapted for portable use for farm purposes.

Within the main-flue B is the grate G, which in the present instance is a water-grate of approved construction, suspended at the rear end by a connecting-pipe, g, encircling the air-flue E, hereinafter described, and thereby forming a partial partition between the fire-box proper and the flue-space in rear, which has the function of the bridge-wall of the ordinary boiler-settings. The air-flue E, thus suspended in the loop of the pipe g, extends rearward in the center of the main flue B, and connects with the air-space of the chambered boiler-head D. The lower part of the main flue B, extending in rear of the grates, is divided off

by a horizontal arch plate or partition, forming a lower air-duct, F, which also extends to the rear, and also connects with the air-space of the chambered head D, thus forming an air-duct, and at the same time a protection for the joint between the flue and boiler.

The head D is formed by double walls, enclosing a space, which I thus utilize for heating air to be supplied to the fire. The outer wall of the head D is perforated above for the admission of air, and the inner wall is provided with openings corresponding with the described air-ducts E and F, with which the head connects. I also provide a damper, L, sliding within the head D and controlling the aperture of duct E, and operated by a suitable handle projecting through the outer wall.

The head D may be connected with the boiler by hinges, and so arranged that close joints may be formed with the ends of the ducts E and F by contact merely, and is provided with a man-hole opposite the flue E, for cleaning, &c. In case, however, an ordinary boiler-head or a water-head is used the air-ducts may pass through and take air from the outside; or in the case of a stationary boiler the air may be drawn through suitable ducts arranged in the setting; but for portable boilers I prefer the chambered head, as this arrangement not only utilizes the otherwise waste heat, but also protects the head from the intense heat.

A steam-jet pipe, S, arranged to convey steam from the boiler, passes down through the smoke-arch and terminates in the duct E, discharging toward the furnace. It is provided with a controlling-valve, s, operated by a rod, H, extending forward within convenient reach of the attendant.

The duct E at its forward end is provided with a nozzle, N, preferably of conical form, and of cast-iron or other material suitable for withstanding great heat, perforated on all sides with small holes, and projecting sufficiently forward above the grate to form a kind of sustaining-finger for the light fuel, such as straw, &c., to prevent its packing, and at the same time to deliver the heated air or superheated steam, or both, directly to the central portions of the incandescent fuel.

Instead of a single nozzle, N, two or more may be used, with suitable branching pipes connecting with the air-duct E; but in general one is sufficient.

5 I provide the front end of the main flue B with a double head, O, the outer wall of which is perforated above for the admission of air, which passes around the connecting-easing of the door-aperture and downward through the 10 perforated cross-bar, on which it rests, and which forms also the support for the front ends of the grate-bars. That portion of the flue B below the supporting-bar is closed by a door, K, which is hinged below upon suitable cleats 15 attached to the projecting end of the flue. I provide also an aperture through the flue and boiler-shell beneath the grate, which is closed by a movable damper, J. The openings j and k are only used for removing the heavy 20 residue of combustion, and at all other times are kept closed.

The operation is as follows: The fire being built in the usual manner upon the grate, the damper L being open, the air-supply is drawn 25 in through the double head D, whence it passes through both ducts F and E, the former supplying air beneath the grates and the latter in the body of fuel upon the grates. This air, which is partially heated in passing through 30 the head D, becomes highly superheated in passing through these ducts, which lie through the entire length of the boiler in the path of and in contact with the heated products of combustion, yet in such relation thereto as not 35 to deprive the heating-surfaces of the boiler of their proper effect.

When desired, a jet of steam may be admitted through the pipe s, which thus not only acts as a blower to draw more air through the 40 tube E, but itself becomes superheated, and in such condition causes a most intense combustion of the incandescent fuel into which it is discharged. Steam alone may be admitted through the tube E by closing the damper L.

45 The beneficial effect of my improvement is greatest in connection with light fuels of the kind described, the combustion of which with cold air is very imperfect, as practical experience has abundantly shown.

50 In ordinary cases a large portion of fuels, such as straw, &c., is only charred, and left unconsumed as a residue, filling up the ash-pit and combustion-chamber. In using such fuels I attain a perfect combustion by my improvements, the only residue being a fine ash in the 55 form of an almost impalpable dust, which is carried off through the stack without sparks. This result is mainly due to the fact that in finely-divided fuels the preliminary combustion

60 is sudden and explosive, and the gases do not become sufficiently heated to ignite where cold air is used; but where superheated air is used the gases are not cooled below the point of ignition, but are immediately inflamed, thus producing a clear white flame, with intense heat, 65 free from smoke.

I have also discovered that the introduction of a small jet of superheated steam, or of steam and air, to the path of the heated gases at the beginning-point of their combustion greatly 70 augments the intensity of their combustion. This I accomplish by the use of the nozzle before described and by the valve, by which the quantity of steam or air may be regulated by the attendant according to the dryness of the 75 fuel or other conditions of use.

The air-ducts E and F may be perforated at intervals in their length, to permit egress of air at other points in the path of the gases of combustion, in order to insure their thorough 80 ignition during their passage through the flue.

Having described my invention, I claim and desire to secure by Letters Patent—

1. In a steam-boiler, the combination, with the main flue B, of one or more air-heating 85 tubes, E, leading the air above the grate, and bottom flue, F, for passing the air under the grate, all constructed and arranged as shown and specified.

2. In a steam-boiler, the combination, with 90 main flue B, of one or more heating-tubes, E, provided with conical perforated discharge-nozzle N and sliding valve L, constructed and arranged substantially as shown, and for the purpose set forth.

3. In a steam-boiler, the combination, with the main flue B, of one or more heating-tubes, E, provided with perforated discharge-nozzle N and sliding valve L, bottom flue, F, and chambered head D, all constructed and arranged substantially as described. 95

4. In a steam-boiler, the combination of the main flue B, placed eccentrically with one or more heating-tubes, E, provided with perforated discharge-nozzle N and valve L, and supported on its inner end by a water-partition or bridge-wall, and its outer end connected to the chambered partition D, all constructed and arranged substantially as specified. 105

5. In a steam-boiler, the combination of the main flue B and one or more heating-tubes, E, and bottom flue, F, with the furnace and a chambered head, O, through which the air is passed above the furnace-door to the lower side of the grate, and thereby heated, constructed 110 substantially as shown and specified. 115

6. The combination, in a boiler and main flue, B, of one or more heating-tubes, E, provided with perforated head N and controlling-valve L, with steam-jet pipes S and the hinged 120 chambered head D, all constructed and arranged substantially as shown, and for the purpose set forth.

7. The combination, in the boiler A, of the tubes C, the main flue B, heating-tubes E, bottom flue, F, water-circulating bridge-wall g, chambered heads D and O, steam-jet pipe S, hollow grate-bars G, and damper J, all constructed and arranged as shown and described. 125

8. In combination with a boiler having a 130 main flue eccentrically arranged therein in contact with the boiler-shell at the bottom, the

flue F, formed by an arched plate dividing off the bottom of the main flue for the protection of the joint and for air-heating purposes, substantially as described.

5 9. The combination of the chambered boiler-head D and air-ducts E and F, all arranged substantially as and for the purpose described.

10. The damper L, in combination with the chambered boiler-head D and air-ducts E and

F, all arranged substantially as and for the purpose described.

In testimony whereof I have hereunto set my hand this 15th day of January, 1880.

WILLIAM MOORE.
